UNITED STATES PATENT OFFICE

2,305,040

MINING CUTTER BIT

Henry M. Stephens, Montgomery, W. Va.

Application December 30, 1940, Serial No. 372,233

2 Claims. (Cl. 262—33)

This invention relates to bit holders and particularly to a mining cutter bit used in connection with the mining of coal and ore or the like, or in such places as require the use of a bit of the type for cutting through a material, and has for its principal object the provision of an improved construction of this character which is highly efficient in use and economical in manufacture.

Among the salient objects of this invention is the provision of an effective and inexpensive arrangement for releasably holding and latching the bit to its chuck.

The present invention relates to an improvement over that shown in my companion applications filed on even date hereof, one bearing Serial No. 372,234 and the other Patent No. 2,262,592 issued November 11, 1941.

Heretofore in the employment of mining cutter bits of the type hereinafter described, due to the lack of firmness in holding the bit in place, a vibratory action would be transmitted to the bit, ultimately resulting in crystallization of the shank thereof and the breakage or dislodgement of the bit from its chuck or holder. In many instances in bits of the type hereinafter set forth, by virtue of the particular and special means adapted for holding the bit in its place upon the chuck, either the chuck or the shank of the bit, in order to make room for the attachment, was greatly weakened and often weakened to the point where, when the bit was subjected to rough usage, breakage at the line of weakened union occurred.

It is therefore one of the many objects of this invention to provide a bit which is attached to the chuck holder in a manner such as will prevent these known disadvantages.

Other objects will appear hereinafter.

The invention consists in the novel combination and arrangement of parts to be hereinafter described and claimed.

The invention will be best understood by reference to the accompanying drawing showing the preferred form of construction, and in which:

Fig. 1 is a side elevational view of the cutter bit assembly;

Fig. 2 is a plan sectional detail view of the same;

Fig. 3 is a fragmentary sectional detail view of the same showing the bit in partially removed position from its chuck or holder; and

Fig. 4 is a perspective view of the bit with portions broken away; and

Fig. 5 is a fragmentary plan view of the bit and holder therefor, showing a modification of construction, with part broken away in section.

To accomplish the many objects of the present

invention, I provide a chuck or holder 10 having the usual eyelets 11 for attachment in chain formation when a plurality of cutter bits are employed in a manner well known in the art of mining.

This chuck includes a transversely extending passage 12 adapted to slidably receive a shank 13, the passage 12 and shank 13 each being formed in cross section to correspond one to the other. The shank 13 is formed as an integral part of a head 14 having a cutter bit socket 15 of a shape which necessitates the insertion and withdrawal of the bit 16 in one direction.

The shank 13 is detachably held in place by a set screw 17, the inner end 18 of which passes into a tapered recess 19 so as to assure a firm and proper wedging relationship between the shank 13 and the inner end portion of the set screw 17. A latch structure generally indicated at 20 is provided for holding the cutter bit 16 in place. In the present instance, this latch structure comprises a dog 21 having a tapering edge 22 corresponding to the tapering edge 23 of the bit 16. This latch dog 21 is further provided with a notched-out portion 24 through which is disposed a key 25 projected through aligned openings 26 formed in the head 14 and adapted to slidably lock the dog 21 in the head 14. The inner end 27 of the dog 21 is preferably flush with the surrounding surface 28 of the shoulder portion 29 of the head 14. This shoulder portion 29 is adapted, when the shank 13 is properly locked in the passage 12, to abut the adjacent surface 30 of the chuck 10. When this shoulder 29 is in this abutting relation, it will be noted that the end 27 of the dog 21 is firmly locked in latching position against the cutter bit 16 so that the same cannot be accidentally displaced from latching position.

40 The recess 19, as shown, is tapered and has an additional function to that which is hereinbefore stated. In this connection this recess 19 permits the shank 13, when the set screw 17 is partially removed from projection in the passage 13, to be withdrawn to the position shown in Fig. 3, whereby to allow the dog 21 to be moved from latching position to allow withdrawal of the cutter bit 16. In this it will be noted that the cutter may be unlatched from its position in the head 14 without the complete withdrawal of the shank 13 from the passage 12 of the chuck 10.

It is significant to note that the construction of the means for latching the bit to the chuck is substantially simple and inexpensive and that by virtue of the relationship of the various parts

when in assembled relation, neither the cutter bit nor the holder or chuck is weakened; that to remove the cutter bit it is necessary first to remove the shank 13 a substantial distance from position in the passage 12 to permit the expeditious movement of the dog from latched position against the bit substantially in the manner shown in Fig. 3.

While I have illustrated and described the preferred form of construction for carrying my invention into effect, this is capable of variation and modification without departing from the spirit of the invention. I therefore do not wish to be limited to the precise details of construction set forth, but desire to avail myself of such variations and modifications as come within the scope of the appended claims.

Having thus described my invention, what I claim as new and desire to protect by Letters Patent is:

1. In combination, a chuck or holder having a passage therethrough, a shank slidably mounted in the passage and provided with a tapering recess in one edge thereof, a set screw adapted to be threaded into said recess, said set screw permitting partial withdrawal of the shank from the passage when partially withdrawn from engagement in said tapering recess, said tapering recess assuring a wedging relationship between the

shank and set screw, a head on said shank having a cutter bit recess, a cutter bit mounted in said recess, and latch means carried by said head and serving to latch the cutter bit in said cutter bit recess, said latch means being incapable of movement from said latched position with respect to the cutter bit when the shank is disposed completely in said passage, said latch means including a latch member having a notched portion formed therein, and a pin member carried by said head and projected transversely of the notched portion to limit movement of the latch means from latched position with respect to the cutter bit.

2. In combination, a tool receiving head, a tool slidably mounted in said head and having a tapering edge, a dog slidably carried by the head and having a tapering edge adapted to engage the tapering edge of said tool for latching said tool in said head, said head having a shoulder adapted to engage an adjacent object, and said dog being held in said latched position by said object, substantially as described, said dog having a notched portion and a pin member carried by the head and projected through the notched portion and serving to limit the movement of said dog from latched position with respect to said tool.

HENRY M. STEPHENS.
